UNITED STATES PATENT OFFICE.

WILLIAM S. DOLBEY, OF BROOKLYN, NEW YORK.

DESIGN FOR A FINGER-RING.

SPECIFICATION forming part of Design No. 15,403, dated September 16, 1884.

Application filed July 3, 1884. Term of patent 7 years.

To all whom it may concern:

Be it known that I, WILLIAM S. DOLBEY, a citizen of the United States, and a resident of Brooklyn, in the county of Kings and State of New York, have invented and produced a new and original Design for Finger-Rings, of which the following is a specification, reference being had to the accompanying drawings, forming part thereof.

10 Figure 1 is a plan view of my newly-designed finger-ring; and Fig. 2, a side elevation of the same, both figures being shown upon an enlarged scale.

15 Like letters of reference indicate corresponding parts in both figures.

Heretofore finger-rings have been made with a square or oblong setting, but such setting has not presented the configuration shown in my design.

A is the shank or annulet having an oval top, as shown, and B is the setting having the form of a shield.

I claim—

The design for a finger-ring herein shown and described, the same consisting of an annulet having an oval top, as shown, a setting therein presenting the outline of a shield, the outer face thereof forming an arc of the periphery of the ring, as set forth.

Signed at New York, in the county of New York and State of New York, this 2d day of July, A. D. 1884.

WM. S. DOLBEY.
